UNITED STATES PATENT OFFICE.

RALPH MODJESKI, OF PHILADELPHIA, PENNSYLVANIA.

REINFORCED BRIDGE SPAN.

1,417,936.

Specification of Letters Patent. Patented May 30, 1922.

Application filed September 26, 1921. Serial No. 503,187.

To all whom it may concern:

Be it known that I, RALPH MODJESKI, a citizen of the United States, and a resident of Philadelphia, in the county of Philadelphia and State of Pennsylvania, have invented a Reinforced Bridge Span, of which the following is a specification.

This invention relates to bridges and relates particularly to railway bridges of the 10 type known as "through" bridges.

It is a matter of common knowledge that within a period of comparatively a few years the character of railroad rolling stock has changed very materially, both locomotives 15 and cars being much larger and heavier and the cars being loaded much more heavily than formerly, thus correspondingly increasing the live load to which bridges are subjected due to the weight of trains passing 20 over them.

As a result of this change, it has been found necessary in many cases to reinforce and strengthen old railroad bridges, or where this was impossible or impractical for 25 any reason, to replace the old structure with a new one of sufficient strength to meet present day requirements while at the same time maintaining traffic on the old structure.

The object of the present invention is to provide a construction for thus reinforcing and strengthening the spans of through bridges, which will involve practically no change in the original bridge structure and 30 will permit the original structure to remain practically undisturbed during the strengthening process.

I effect the object of the invention by means of what may be designated a supplementary span erected between the trusses of the original span, said supplementary span being erected at a sufficiently higher level than the original span so that it will be entirely above the floor of said original 45 span, which will thus present no obstruction to the erection of said supplementary span and need not be disturbed, web members of the trusses of said supplementary span being extended downwardly—forming hanger 50 members—and being riveted to the floor beams of the original span, whereby a proportionate part of the live load on the span and, under certain conditions, of the dead load, will be transferred to and borne by 55 said supplementary span.

Also, in order that deflection and other

distortion of the original and supplementary spans under load shall be the same, or proportionate, said supplementary span is, 60 geometrically, substantially a duplicate of the original span, the aggregate cross sectional areas of different parts and members of said supplementary span being such part of the aggregate cross sectional areas of corresponding parts or members of the original 65 span, as the designed increase in the strength of the span is of the strength of the original span.

The trusses of the supplementary span may be cross braced or not as desired. In 70 case they are cross braced, the cross braces of the supplementary span, so far as practicable, will preferably be built around corresponding bracing members of the original span so as to enclose them, thus avoiding 75 interference with the bracing of the original span and leaving it practically intact. If not cross braced, the trusses of the supplementary span may and preferably will be supported against lateral stresses, as wind 80 pressure, by connecting them to the trusses of the original span on the same sides of the bridge. Convenient means for this purpose consists of angle brackets secured to the upright truss members of the supplementary 85 span and to the top chords of the trusses of the original span. If considered desirable, my invention contemplates the use both of cross bracing and connecting brackets.

If it is desired that the supplementary span, 90 in addition to carrying its proportionate share of the live load, shall also carry part of the dead load represented by the weight of the original span, this may be effected by stressing the supplementary span so as to deflect it, or by relieving the stresses in the original span so as to increase its camber, before connecting the hanger web members of said supplementary span to the floor beams of the original span, or, preferably, 95 by both stressing the supplementary span and relieving the stresses in the original span. Simple means for this purpose may consist in connecting original and supplementary spans by rods comprising sections 100 connected by turn-buckles, which will thus form in effect lifting jacks. My invention, however, contemplates the use for this purpose of any form of lifting means such as will readily suggest themselves to bridge 105 engineers and others skilled in the erection 110 of this type of structure.

A reenforced bridge structure of my invention also comprises the various other features, combinations of features and details of construction hereinafter described and claimed.

In the accompanying drawings, in which my invention is fully illustrated,

Figure 1 is a side view of a through bridge span reinforced in accordance with my invention.

Figure 2 is a sectional elevation thereof comprising right and left hand half sections taken on the lines 2—2 and 2'—2', respectively, of Fig. 1.

Figure 3 is a fragmentary side view, on an enlarged scale, of the footings for supporting the ends of the original and supplementary spans of a bridge reenforced in accordance with my invention, and also for supporting and connecting the adjacent ends of the spans of a bridge comprising more than a single reenforced span.

Figure 4 is an end view from the position 4—4 of one of the spans in Fig. 3.

Figure 5 is a top plan view of the parts shown in Figs. 3 and 4.

Figures 6 and 7 are fragmentary sectional elevations taken on the lines 6—6 and 7—7, respectively, of Fig. 2, and

Figures 8, 9 and 10 are fragmentary detail views taken, substantially, from the positions 8—8, 9—9 and 10—10, respectively, of Fig. 2.

Referring now to the drawings, A designates, as a whole, the original or old span of a bridge reenforced in accordance with my invention, and B the supplementary or new span, said spans respectively comprising trusses A' A² and B' B². Excepting in minor and unimportant details, said spans A, B, and the trusses forming parts thereof, respectively, are geometrically duplicates of each other.

As regards their usual features and excepting as to features hereinafter particularly pointed out and described, the spans A and B, shown, are merely typical—exemplifying generally the application of my invention and improvements for reinforcing and strengthening all types of the through bridges, where trusses of original spans are spaced far enough apart to its use.

As regards their usual features, also, the construction of said spans and trusses will be readily understood by bridge engineers and other familiar with bridge design from an examination of the drawings, without description thereof in detail.

What may be considered the basic feature of my invention, consists in erecting the supplementary span B at a sufficiently higher level than the original span that said supplementary span will be entirely above the floor of the original span and may thus

be erected without tearing out the floor and without disturbing it, excepting in very slight respects.

In carrying out my invention, as it relates to this broad feature, I provide new 70 footings for supporting the supplementary span erected on the original piers or foundation of the bridge, indicated at C, said new footings being positioned between and closely adjacent to the shoes of original 75 span, designated D. For purposes of convenient reference, said new footings will be designated as a whole D'.

As shown, said footings D' comprise blocks 1, consisting preferably of steel castings, which rest directly upon the tops of the piers C, girders 2, the ends of which rest upon said blocks 1 and are connected by diaphragms 3, and shoes 4 supported by said girders and diaphragms, resting directly upon cover plates 5 secured to the tops thereof.

In the preferable construction shown, also, all of the footings D, D' for both spans at the same ends thereof, are rigidly connected or tied together by connecting the ends of the girders 2 to plates 6 inserted beneath the ends of the trusses A', A² and resting upon the top sides of the shoes D for the original span, as shown at 7, Fig. 4. 95

In the drawings, I have shown my invention and improvements, as they relate to the footings of supplementary spans, as applied for supporting the contiguous ends of adjacent spans of bridges comprising a plurality of spans. The adaptation thereof for reinforcing bridges consisting of only one span, will, however, involve no departure in principle from the application shown, and will be obvious to persons familiar with 100 bridge construction and design from the disclosure of the drawings.

In order that the supplementary span B shall carry a predetermined proportionate share of the loads to which the bridge is 110 subjected in use, web members of the trusses B', B², of the supplementary span B are extended downwards and are riveted or rigidly attached to the floor beams 8 of the bridge.

If the supplementary span B is designed to strengthen the bridge under live loads only, the members of said supplementary trusses will be connected to the floor beams 120 of the bridge, while under normal deflection only, due to its own weight.

If, on the other hand, said supplementary span is designed to carry a portion of the dead load represented by the weight of the original span A, this may be effected by 125 stressing the trusses B', B² thereof to increase their deflection to correspond to a desired dead loading thereof before the web members of said trusses are connected to the floor beams 8 of the bridge—or, what 130

would amount to the same thing, by relieving the stresses in the trusses of the original span A to increase their camber, or by both stressing the trusses of the supplementary span 5 and relieving the stresses in the trusses of the original span to increase the deflection and camber thereof, respectively. Means for this purpose will readily suggest themselves to engineers and erectors and, as 10 they form no part of the invention per se, it is unnecessary to either show or describe the same.

As shown, the trusses A', A'', and B', B'' are connected by sway bracing of the character 15 commonly used on relatively long, high spans. Said sway bracing will be readily understood by bridge engineers from an examination of the drawings and it need not, therefore, be described in detail, excepting 20 as regards certain features peculiar to bridges reenforced in accordance with my invention.

One such feature is presented by certain of the web members of the trusses of the 25 supplementary span which extend down and connect to the floor beams of the bridge and which comprise spaced shapes connected by batten plates or lacing, the characteristic feature of which is that said shapes are disposed 30 on opposite sides of the floor beams to which they are to be connected, respectively, as shown particularly in Fig. 7.

Another such feature is shown in Fig. 6 of the drawings and has particular reference 35 to sway braces of the original span which intersect web members of the supplementary span consisting of rigidly connected spaced structural shapes. One characteristic feature illustrated in said Fig. 6 is that the 40 structural shapes forming said members are positioned on opposite sides of said bracing and are spaced a sufficient distance apart to permit said bracing members to pass between them.

Still another feature, also shown in Fig. 6, relates to sway bracing of the original and supplementary spans consisting of structural shapes secured together in spaced relation by lattices, batten plates or the like, and 50 which extend parallel with and normally would be positioned one above the other a distance equal to the elevation of the supplementary span above the original span. As regards this feature, I contemplate lowering 55 the bracing of the supplementary span so that its axis will coincide substantially with the axis of corresponding bracing of the original span, and building the bracing of the supplementary span around that of the original span so as to enclose said 60 original bracing and conceal the same, thus obviating interference of the new bracing with the old and rendering the sway bracing of the reenforced structure less intricate 65 and more slightly in appearance.

In accordance with my invention, also, the trusses of the original and supplementary spans on the same side of the bridge are rigidly connected together, thus imparting stiffness and rigidity to the reenforced 70 structure to resist lateral stresses. Simple means for this purpose consists of angle brackets 9, which either connect the top chords of the trusses of said original and supplementary spans directly, as shown in 75 Figs. 2 and 9, or the top chord of the original span with web members of the trusses of the supplementary span adjacent to the top chords thereof, as shown in Figs. 2 and 8.

Also, if the sway bracing of the original span is sufficiently strong or can be reenforced to make it sufficiently strong to support the trusses of both spans of the reenforced bridge against lateral stresses, my 85 invention contemplates dispensing entirely with sway bracing for the supplementary trusses and supporting the same against lateral stresses by connecting the trusses thereof to the trusses of the original span by 90 brackets, in the manner described. Or, if desired, my invention contemplates the use of both forms of sway bracing for said supplementary span.

I claim—

1. In a reenforced bridge structure the combination of an original span comprising trusses, end supports therefor, and a floor comprising transverse floor beams, a supplementary span comprising trusses, and end 100 supports therefor positioned sufficiently higher than the end supports for the original span that said supplementary span will clear the floor of the bridge, the trusses of said supplementary span comprising web members which are extended down and are connected to the floor beams of the bridge, substantially as described.

2. A reenforced bridge structure as specified in claim 1, in which said trusses are substantially geometrical duplicates of each other, substantially as described.

3. A reenforced bridge structure as specified in claim 1, in which the floor of the bridge comprises girders the ends of which 115 are built into and rigidly connect the end supports for the trusses of the supplementary span at opposite sides thereof, substantially as described.

4. A reenforced bridge structure as specified in claim 1, in which the end supports for corresponding ends of the trusses of the original and supplementary spans are rigidly connected, substantially as described.

5. A reenforced bridge structure as specified in claim 3, in which the end supports for corresponding ends of the trusses of the original and supplementary spans are rigidly connected, substantially as described.

6. A reenforced bridge structure as speci-

95

100

105

115

120

125

130

fied in claim 3, in which the end supports for the trusses of the supplementary span comprise base blocks on which the floor girders incorporated into the end supports of said supplementary span rest, substantially as described.

7. A reenforced bridge structure as specified in claim 2, in which the trusses of the original span are connected by sway bracing, and the trusses of the original and supplementary spans on the same side of the bridge are rigidly connected to each other adjacent to their top chords, substantially as described.

10 8. A reenforced bridge structure as specified in claim 2, in which the trusses of the original span are rigidly connected by sway bracing, the web members of the trusses of the supplementary span intersected thereby comprising spaced members so disposed that said intersecting sway bracing will extend between the same, substantially as described.

15 9. A reenforced bridge structure as specified in claim 8, in which trusses of the original and supplementary spans on the same side of the bridge are rigidly connected adjacent to their top chords, substantially as described.

20 10. A reenforced bridge structure as specified in claim 1, in which the trusses of the original and supplementary spans are rigidly connected by sway bracing, comprising bracing for said spans, respectively, the axes of which are substantially coincident, and the 25 bracing for said supplementary span is built around and incloses the bracing for said original span, substantially as described.

11. A reenforced bridge structure as specified in claim 10, in which the sway bracing

for the original span intersects web members 40 of the trusses of said supplementary span and the web members of said supplementary span intersected thereby comprise spaced members so disposed that the intersecting sway bracing will extend between the same, 45 substantially as described.

12. A reenforced bridge structure as specified in claim 1, in which the trusses of the supplementary span are deflected before the web members thereof are connected to the 50 floor beams of the original span, to transfer a portion of the dead load represented by the weight of the original span to said supplementary span, substantially as described.

55 13. A reenforced bridge structure as specified in claim 1, in which the stresses in the original span are relieved to increase its camber before the web members of the supplementary span are connected to the floor 60 beams of said original span, to transfer a portion of the dead load represented by the weight of the original span to said supplementary span, substantially as described.

14. A reenforced bridge structure as specified in claim 12, in which the stresses in the original span due to its weight are relieved, 65 substantially as described.

15. A reenforced bridge structure as specified in claim 1, in which the trusses of the 70 supplementary span are erected inside of the trusses of the original span, substantially as described.

In testimony that I claim the foregoing as my invention, I have hereunto affixed my 75 signature this fifteenth day of September, 1921.

RALPH MODJESKI.
